UNITED STATES PATENT OFFICE.

HERMAN F. RENGSTORF, OF WATERLOO, ILLINOIS.

COLLAPSIBLE DRINKING-CUP.

1,037,985.

Specification of Letters Patent. Patented Sept. 10, 1912.

Application filed November 22, 1911. Serial No. 661,780.

To all whom it may concern:

Be it known that I, HERMAN F. RENGSTORF, a citizen of the United States, residing at Waterloo, in the county of Monroe and State of Illinois, have invented certain new and useful Improvements in Collapsible Drinking-Cups, of which the following is a specification, reference being had therein to the accompanying drawing.

10 This invention relates to drinking cups of the collapsible type and the principal object of the same is to provide the cup with a novel type of handle which supports the cup when in use and which holds the cup in 15 a closed position and holds the cover of the cup in place when the cup is closed.

This invention is illustrated in the accompanying drawings, wherein—

Figure 1 is a vertical sectional view taken 20 through the cup in a set up position. Fig. 2 is a vertical sectional view through the cup in a folded position. Fig. 3 is a detail plan view of the cup in a folded position. Fig. 4 is a bottom plan view of the lower section 25 of the cup.

Referring to the accompanying drawings by numerals it will be seen that this invention comprises the telescoping sections 10, 11 and 12, the upper section 12 having its 30 edge rolled about a ring 13. A handle 14 has its upper portion 15 connected with the ring 13 and has its lower portion 16 terminating in a hook portion 17. The lower section 10 is provided with a bottom 18 35 which extends beyond the section 10 to form the ledge 19, and is then bent to form a second ledge 20, the ledge 20 being provided with the oppositely disposed cut-out portions 21 and 22.

40 When this cup is in a folded position, the section 11 rests upon the ledge 19 and the upper section rests upon the ledge 20. The handle is moved so that the upper portion 15 extends along one side of the cup and 45 through the cut-out portion 21. The handle extends across the bottom of the cup and through the cut-out portion 22 and up the opposite side of the cup. After the cup has been folded the cover 23 is placed upon the 50 upper portion and has one side inclosing the

hinged end of the cover and the opposite side engaged by the hook portion 17 of the handle.

When it is desired to use the cup, the hook portion 17 is released from the cover, and 55 the cover removed. The handle is then wound around the cup and the sections drawn out to the position shown in Fig. 1, with the hook 17 engaging the bottom of the lower section. It will thus be evident that 60 the same means which holds the cover 23 in place when the cup is in a folded position may be used as a handle for carrying the cup when the cup is in a set up position.

What is claimed is:—

1. A collapsible receptacle having its lower section provided with oppositely disposed cut-out portions, a handle hinged to the upper section of said receptacle, a cover for said receptacle, the free end of said handle being adapted to be passed through one of said cut-out portions to engage the bottom of said receptacle to hold said receptacle in a set up position, and said handle being adapted to pass through said cut out portions and having its upper end engage said cover to hold the same upon said receptacle when in a folded position. 65

2. A collapsible receptacle, a cover therefor, an enlarged base carried by the lower section of said receptacle, said base being provided with oppositely disposed cut out portions, a handle pivotally connected with the upper section of said receptacle, said handle being formed from a strip of material having its free end bent to form a hook fitting beneath said base to support said receptacle when in an extended position, said strip passing through said cut out portions and up the side of said receptacle when in 80 a folded position with its free end in a position to engage said cover to hold said cover upon said receptacle. 85

In testimony whereof I hereunto affix my signature in presence of two witnesses.

HERMAN F. RENGSTORF.
